UNITED STATES PATENT OFFICE.

MARY A. MARTIN, OF DETROIT, MICHIGAN.

DESIGN FOR A TOY BANK.

SPECIFICATION forming part of Design No. 27,442, dated July 27, 1897.

Application filed June 17, 1897. Serial No. 641,205. Term of patent 7 years.

To all whom it may concern:

Be it known that I, MARY A. MARTIN, a citizen of the United States, residing at Detroit, in the county of Wayne, State of Michigan, have invented and produced a new and original Design for Toy Banks, of which the following is a specification, reference being had to the accompanying drawings, and to the letters of reference marked thereon, which form a part of this specification.

This invention relates to a new and original design for toy banks; and it consists in the formation and contour illustrated in the accompanying drawings, in which—

Figure 1 is a perspective view of my design for a toy bank. Fig. 2 is a transverse section therethrough on line 2 2 of Fig. 1. Fig. 3 is an inverted plan of said design.

The leading feature of my design consists in the general shape or configuration shown in the accompanying drawings, which describes an oblong shell A, traversed longitudi-

nally of its body by a medial line a and having in the surface of the body portion thereof indentations b.

Formed through the upper face of the body or shell is an elongated opening c, which stands parallel to the length of said body, while the bottom of said body or shell is provided with a flat surface d, forming a base, the whole presenting a design for a toy bank of original and peculiar shape.

Having thus fully set forth my invention, what I claim as new, and desire to secure by Letters Patent, is—

The design for a toy bank substantially as herein shown and described.

In testimony whereof I affix my signature in presence of two witnesses.

MARY A. MARTIN.
